FOREIGN PATENT DOCUMENTS

EP 1847463 10/2007

Primary Examiner — Vy N Koenig(74) *Attorney, Agent, or Firm* — Buche & Associates,
P.C.; John K. Buche; Bryce A. Johnson(57) **CLAIM**

We claim the ornamental design for a child-resistant package, as shown and described.

DESCRIPTION

FIG. 1 is a perspective view of a child-resistant package showing our new design;

FIG. 2 is a front view of the child-resistant package of FIG. 1;

FIG. 3 is a back view of the child-resistant package of FIG. 1;

FIG. 4 is a side view of the child-resistant package of FIG. 1;

FIG. 5 is a side view of the child-resistant package of FIG. 1;

FIG. 6 is a top view of the child-resistant package of FIG. 1;

FIG. 7 is a bottom view of the child-resistant package of FIG. 1; and,

FIG. 8 is a top plan view of the interior surface of the child-resistant package of FIG. 1 in an unfolded blank configuration.

Broken lines depict portions of the child-resistant package and form no part of the claimed design.

1 Claim, 4 Drawing Sheets(56)
